UNITED STATES PATENT OFFICE.

SYDNEY MARQUIS, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

STEAM-TURBINE.

1,187,445.

Specification of Letters Patent. Patented June 13, 1916.

Application filed February 9, 1914, Serial No. 618,154. Renewed December 3, 1915. Serial No. 65,398.

To all whom it may concern:

Be it known that I, SYDNEY MARQUIS, a citizen of the United States, residing at West Allis, Milwaukee, in the county of Milwaukee and State of Wisconsin, have invented a certain new and useful Improvement in Steam-Turbines, of which the following is a specification.

This invention relates to steam turbines and more particularly to a method of securing the shroud to the blade ends and for properly positioning the blades at one end.

An object of the invention is to provide an assembled blade structure for steam turbines which is simple in construction, efficient in operation, and which possesses the requisite amount of rigidity and strength, especially to withstand vibration.

One of the more specific objects of the invention is to provide efficient means for securing a comparatively light shroud to the ends of a plurality of blades by fusion of metal, this shroud being imperforate and being provided with means in the form of a recessed projection, for properly positioning the blade ends.

Another object is to provide a shroud having side projections which coact with edge portions of the blades in order to properly align the blade ends in a direction transversely of the row of blades.

Heretofore it had been proposed to fasten a shroud to the ends of blades by fusion of metal, for instance by brazing, the blade ends having been properly positioned by forming a tenon on the blade and inserting the same in a hole formed in the shroud. The objections to this construction are, first, that considerable of the blade stock is wasted in forming the tenon; and second, that the shroud is weakened at least temporarily, by forming the holes therein for the tenons. With the use of the present invention these objections are eliminated.

A clear conception of an embodiment of the invention may be had by referring to the drawing accompanying and forming a part of this specification in which like reference characters designate the same or similar parts in the various views.

Figure 1 is an elevation of a fragment of a shroud attached to a plurality of blade fragments. Fig. 2 is a transverse section through the blades, the section being taken

along the line II—II of Fig. 1 looking in the direction of the arrows. Fig. 3 is a transverse vertical section through a shroud attached to a fragment of a blade and showing a fragment of the stationary casing, the section being taken along the line III—III of Fig. 2. Fig. 4 is a transverse vertical section through a shroud attached to a fragment of a blade and showing a fragment of the stationary casing, the section being taken along the line IV—IV of Fig. 2.

While the figures of the drawing disclose rotor or movable blading of a turbine of the parallel flow type, it is to be understood that the invention is equally applicable to stator or stationary blading as well as to other types of turbines. The shroud 2, which is preferably made as light as possible, is provided on its blade side with a pair of side projections 4 and an intermediate projection 7, these projections prior to being notched for insertion of the blade ends being continuous throughout the length of the shroud stock. The intermediate projection 7 is considerably larger than the side projections 4.

In order to permit proper positioning of the blade ends, the projections 4, 7, of the shroud 2, are recessed by removal of the metal to form the recesses 8. This removal of the metal is accomplished by the use of a saw, broach, milling cutter or other suitable means, which may be operated rectilinearly across the entire inner face of the shroud 2, thereby simultaneously forming alined recesses 8 in all of the projections 4, 7.

After the side projections 4 and the intermediate projection 7 of the shroud 2 have been properly recessed, the shroud 2 is applied to the ends of the blades 1 which have been previously fixed in a suitable foundation segment in the usual manner. In order to permit insertion of the ends of the blades 1 within the recesses 8 formed in the projection 7, the edge portions of the blade ends are slightly notched, see Fig. 4, these notched portions of the blades coacting with the side projections 4. After the shroud 2 has been applied to the ends of the blades 1, the blades and shroud are united by fusion of metal by any suitable process, such as soldering, brazing, or welding.

The outer surface of the shroud 2 with the structure complete is finished in the form of

a cylindrical surface, which with the turbine assembled, operates in close proximity to the stationary turbine casing 3.

It will be noted that the recesses 8 formed in the side projections 4 are not utilized in positioning the blades 1, the production of these recesses merely facilitating the operation of recessing the intermediate projection 7. The portions of the side projections 10 4 which remain after the recesses 8 have been cut, serve to properly align the blade ends in a direction transversely to the row of blades 1. The recesses 8 formed in the intermediate projection 7 serve to properly 15 space and angle the blade ends, the angling and spacing of the blade ends being determined by the direction and location of the recesses 8 in the projection 7. This mode of recessing a projection on a shroud is contrarily distinguished from the mode of forming a shroud with a series of individual projections with recesses left between them, although the original projection is in fact altered to form divisional projections after 20 recessing. The present mode of recessing a projection insures that the recess will coact with the working faces of the blades longitudinally to a maximum extent.

It will be noted that by the use of the 30 form of shroud 2 as disclosed, the blade ends can be united by fusion of metal directly to the surface of the shroud 2 adjacent these ends without necessitating waste of blade stock such as results from forming spacing 35 and angling tenons on the blades 1. The

combination of an imperforate shroud having a recessed projection with a plurality of blades united thereto by fusion of metal results in a structure having great rigidity and strength.

It should be understood that it is not desired to be limited to the exact details of construction shown and described except as required by the scope of the appended claims, for obvious modifications will occur 45 to a person skilled in the art.

It is claimed and desired to secure by Letters Patent,—

1. The process of providing a blade with a shroud comprising, producing a shroud with a continuous projection, forming a recess in said projection, applying said shroud to the end of said blade at said recess, and uniting said blade and said shroud by fusion of metal.

2. The process of providing a blade with a shroud comprising, producing a shroud with a continuous longitudinal projection, removing a portion of said projection, applying said shroud to the end of said blade 60 at said removed portion, and uniting said blade and said shroud by fusion of metal.

In testimony whereof, the signature of the inventor is affixed hereto in the presence of two witnesses.

SYDNEY MARQUIS.
